UNITED STATES PATENT OFFICE.

GEORGE F. EBERHARD, OF TRENTON, NEW JERSEY, ASSIGNOR TO ROBT. H. INGERSOLL & BRO., A JOINT-STOCK ASSOCIATION ORGANIZED UNDER THE LAWS OF NEW YORK.

METHOD OF MAKING WATCH BACKS AND BEZELS.

1,204,257.

Specification of Letters Patent. Patented Nov. 7, 1916.

Application filed December 30, 1913. Serial No. 809,556.

To all whom it may concern:

Be it known that I, GEORGE F. EBERHARD, a citizen of the United States, residing at Trenton, New Jersey, have invented certain new and useful Improvements in Methods of Making Watch Backs and Bezels, of which the following is a specification.

My invention relates to a method for providing watch case backs or bezels with screw threads, at the inner side of their edges.

In the drawings Figure 1 is a sectional view of a blank which is to be threaded; Fig. 2 shows this blank with its edge turned or curled in upon itself ready for the swaging operation; Fig. 3 represents a portion of the completed back or bezel; Fig. 4 is a top view of the machine; Fig. 5 is an enlarged view of the threaded punch or head, with upsetting means to engage the beaded or curled edge of the blank.

In carrying out my invention, I take a blank like that shown in Fig. 1, and with a beading machine of the ordinary type the edge of the blank is curved or turned inwardly, as shown in Fig. 2. This blank is then placed in a die 6, Fig. 4, mounted on a shaft 7 journaled in suitable bearings in a frame 8, and having a pulley 9 thereon by which the die may be rotated. Opposite this die a punch or head 10 is located, having a screw thread at 11 of the pitch desired to be made in the edge of the blank. This head or punch is swiveled at α to and carried by a plunger which may be operated to and from the die by any suitable means; for instance, the toggle 12 operated by a handle 13 or by power in any desired way. The plunger carrying the punch or screw threaded head moves through a bearing 14, and it extends through a slide 15 which has mounted thereon means for upsetting the beaded edge of the blank against the screw threads of the punch or head. This means may assume various forms, and may consist of devices disposed at different points about the circumference of the head, and in the particular form shown the said means or devices consist of rollers 16 mounted on the slide 15, any suitable form of bearings being provided for this purpose consisting in the present instance of the arms 17 extending from the slide. The rollers are journaled to these arms, and they lie close adjacent the side of the punch or head 10, and

with their peripheries adjacent the base of the thread formed in the side of said punch or head. The slide may be advanced with the punch or head by any suitable means. In the particular construction shown, the handle or lever 18 is representative of any suitable connection or means that may be employed for advancing and retracting the slide with the upsetting means or devices attached thereto.

In the operation of the machine the die with the blank contained therein is rotated, and the head or punch 10 is advanced so that the threaded portion of said head or punch will enter the blank and be located closely adjacent to the inner side of the curled or beaded edge, the slide 15 will also be advanced, and its swaging rollers will engage the beaded edge of the blank, and as the blank is turned by the revolution of the die 6 all parts of this beaded edge will be acted upon by the rolls or swaging elements of other forms that may be used, and the beaded edge will therefore be upset or deformed and the metal thereof will be flowed into the threads of the punch, it being understood that during this action the head 10 will turn with the die and blank all as one body. Upon retraction of the punch the cup-shaped back or bezel may be turned off from the threaded punch. It will be understood that as the punch, die and the swaging or upsetting means associated with the punch come together, the metal of the beaded edge will be confined by these parts, and the pressure resulting from the contact of the swaging element or elements will cause the upsetting of the edge just described.

It will be understood that the invention is not limited to two rollers or swaging elements, as more or less upsetting elements may be employed.

By the use of my invention the escape of any of the metal from between the die and punch is avoided, this surplus metal being known in the art as "flash."

The machine may be operated by hydraulic pressure, compressed air or other power.

By my method the bead or curled edge of the blank is upset against the threading punch or member by a progressive action due to the relative rotation of the female die and the swaging members.

After the swaging operation has been

completed by all parts of the edge of the blank passing under the roll or rolls, the revolution of the die is reversed and the back or bezel is thereby unscrewed from the 5 head or punch, and another blank is inserted in the die and the operation repeated.

I claim as my invention:—

1. The herein described process consisting in turning inwardly the edge portion 10 of a cup-shaped member, holding said member in a cup-shaped die, operating a punch having a screw thread on its lateral face within the cup-shaped member and die and by pressure exerted progressively along the 15 said turned edge and in a direction parallel with the axis of the punch and die and across the holding surface of the die progressively upsetting the metal of the turned edge in a direction transverse to the punching action and into said screw threads on 20

the lateral face of the punch substantially as described.

2. The herein described process of screw threading a member having a rim consisting in holding the member between a female die and a punch having screw threads, and then exerting pressure progressively along the rim of the member so held and in a direction parallel with the axis of the punch and die and thereby upsetting the 25 metal of the rim in a direction transverse to the punch axis and into said screw threads on the lateral face of the punch, substantially as described.

In testimony whereof I affix my signature 30 in presence of two witnesses.

GEO. F. EBERHARD.

Witnesses:

CHARLES H. MARGERUM,
JOHN BATES.
